Thomas Hopper
By George E. Hale
Atty.

UNITED STATES PATENT OFFICE.

THOMAS HOOPS, OF MIDDLETOWN, CONNECTICUT.

DIE.

Application filed June 4, 1921. Serial No. 474,975.

To all whom it may concern:

Be it known that I, THOMAS HOOPS, a citizen of the United States, residing at Middletown, in the county of Middlesex 5 and State of Connecticut, have invented certain new and useful Improvements in Dies, of which the following is a specification, reference being had therein to the accompanying drawings.

10 My invention relates to new and useful improvements in dies and has for its object, among other things, to provide a die that will support a blank thereon during an expanding operation thereon, portions of the 15 die traveling with the expanding portions of the blank through the action of the expanding tool.

To these and other ends, my invention consists in the die, having certain details of 20 construction and combinations of parts, as will be hereinafter described and more particularly pointed out in the claims.

Referring to the drawings, in which like numerals of reference designate like parts 25 in the several figures;

Figure 1 is a fragmentary plan view of my improved die;

Figure 2 is a similar elevation thereof;

30 Figure 3 is a view of a blank ready for operation by the expanding tools; and

Figure 4 is a view of the same blank after it has been subjected to the expanding operation.

My improved die is especially designed 35 for use in supporting a blank while portions thereof are being expanded or spread into a weldless or solid eye, although not necessarily limited thereto.

The blank as presented to the die and 40 produced by a preceding operation, is shown in Figure 3, and after being subjected to the operation performed by the tools in connection with the die herein shown, is illustrated in Figure 4.

45 In the expanding or spreading operation it is essential that the moving portions of the blank be supported while the expanding tool is operating thereon and at the same time not interfere with the operation of 50 the expanding tool, a result obtained in my improved die.

In the drawings, the reference numeral 10 designates the base of the die having a lug 11 projecting from each side thereof 55 with an opening or hole 12 therethrough that provides a convenient means for fast-

ening the die to a press or similar machine.

In the top of the base is a recess 14, the bottom of which I preferably, but not necessarily, cover with a wearing plate 15 60 of hardened material. An opening 13 extends through said plate 15 and that portion of the base immediately adjoining.

Slidably mounted within said recess 14 are the slides or moving platforms 16 which 65 are held therein by the caps 17 secured to the base 10 by the bolts 18 or similar means. A stop member 19 is adjustably secured to the base by a screw 20 or by similar means and is designed to determine the relative 70 position of the blank thereon.

The springs 22, which are supported at one end within the recesses 23 in the slides 16 and at the other end in the recesses 24 in the base 10, exert their tension so as to 75 always maintain the slides in a position wherein their inner faces abut against each other, as shown in Figure 2, this tension being varied by means of the screw plugs 25 threaded into the outer end of the recesses 24.

Extending across the recess 14, and let into the slides or platform 16, so that the upper surfaces thereof and of said slides or platforms are flush with each other, are 85 the plates 28, which support the opposite ends of the blanks during the movement of said slides or platforms.

In operation, a blank 29, such as shown in Figure 3, is placed upon top of the slides 90 or platforms 16 with one end of the blank against the stop 19, at which time the expanding tool 21 is opposite the recess 26 in the upper side of the blank. Movement of the tool 21 causes the same to enter said 95 recess and that portion of the blank upon either side of the recess is moved or spread outwardly. Such moving portions travel upon the top of the slides or platforms 16 until the point of the tool 21 enters the 100 recess 27 formed in the upper meeting edges of the said slides. Thereafter, during the movement of the expanding tool 21, the slides are forced apart against the resistance of the springs 22 and support the expanding or moving portions of the blank 105 upon the top thereof during this movement. During the return movement of the expanding tool 21 the slides 16 move inwardly toward each other through the action of 110 the springs 22 until their inner faces are in contact.

By providing a die with slides or moving platforms 16, as herein shown and described, that portion of the blank which is moved laterally by the action of the expanding tool 21 is supported during the entire expanding operation.

There are minor changes and alterations that can be made within my invention and I would therefore have it understood that 10 I do not limit myself to the exact construction herein shown and described but claim all that falls fairly within the spirit and scope of the appended claims.

What I claim as new and desire to secure 15 by Letters Patent, is,—

1. In combination with a tool, a die comprising a base, slides or platforms movably mounted thereon, and means for moving said slides toward each other, said slides or platforms being actuated in one direction by the action of said tool.

2. In a die, the combination with a base member, having a recess in one face thereof; of slides or platforms movably mounted 25 therein; means for holding said slides within said recesses; and yielding means for moving said slides within said recesses toward each other.

3. In combination with the base; of a tool, 30 and means connected with said base and actuated in one direction by said tool for supporting a blank during lateral movement thereof in relation to said tool.

4. In combination with a tool; of a base; 35 and yielding means connected with the base for supporting a blank during the movement of said tool, portions of which are being spread apart relatively by said tool.

5. In combination with a tool; of a die 40 mechanism of the character described comprising a plurality of slides or platforms yieldingly mounted therein, the inner faces of which are shaped to form a recess in the top surface thereof, which slides or platforms are moved away from each other by 45 engagement of said tool which first enters the said recess.

6. In a die, the combination with a base member; of a plurality of slides or platforms movably mounted therein, said slides or platforms having a recess formed therebetween in one face thereof; and yielding means for moving said slides or platforms toward each other.

7. In a die, the combination with a base 55 member; of a plurality of slides or platforms movably mounted therein, said slides or platforms having a recess formed therebetween in one face thereof; yielding means for moving said slides or platforms toward each 60 other; and means for adjusting the tension of said yielding means.

8. In a die, the combination with a base member; of a plurality of slides or platforms 65 movably mounted therein, said slides or platforms having a recess formed therebetween in one face thereof; yielding means for moving said slides or platforms toward each other; and means connected with said die for locating the blank to be operated 70 upon relatively to said slides.

9. In combination with a tool, a die mechanism having a base, slides or platforms movably mounted thereon, means for moving said slides toward each other, said slides 75 or platforms being actuated in one direction by the action of said tool; and means for supporting a portion of a blank, being operated upon, upon non-movable portions of the die.

10. In combination with a tool, a die for 80 operating upon a blank wherein a portion thereof remains stationary and another portion is moved laterally in relation to the said tool, and comprising a base member, a plurality of slides or platforms movably mounted therein to support the moving portion of said blank, and stationary means adjacent to said slides or platforms for determining the 85 position of said blank.

In testimony whereof, I have hereunto affixed my signature.

THOMAS HOOPS.
